Assistant Examiner — Yuan Yuan

(57) **CLAIM**

The ornamental design for a magnetic alphabet maze, as shown and described.

DESCRIPTION

FIG. 1 is a top perspective view of a magnetic alphabet maze, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view thereof shown in a state of use.

1 Claim, 9 Drawing Sheets
